FIG. 2

FIG. 3

FIG. 4

FIG. 5

FIG. 1

FIG. 6

FIG. 9

FIG. 7

FIG. 8

FIG. 10

FIG. 1 is a perspective view of a desk organizer showing my new design, wherein the front surface is embellished with a calendar, the rear surface being plain and unornamented;

FIG. 2 is a front elevational view thereof;

FIG. 3 is a side elevational view thereof, the opposite side being a mirror image thereof;

FIG. 4 is a top plan view, and

FIG. 5 is a sectional view on the line 5—5 of FIG. 4;

FIG. 6 is a perspective view of another embodiment of the desk organizer shown in FIG. 1 wherein the exterior surface is embellished with a world map;

FIG. 7 is an elevational view thereof;

FIG. 8 is a top plan view thereof;

FIG. 9 is a sectional view taken on line 9—9 of FIG. 8; and

FIG. 10 is a developed plan view of the exterior surface of the embodiment shown in FIG. 6.

The dominant feature of the invention resides in the configuration of the common divider element on the interior of the desk organizers and in the cylindrical shape of the organizers. The configuration of this divider ele-

ment is more particularly shown in FIGS. 1, 4, 5, 6, 8 and 9.

I claim:

The ornamental design for a desk organizer, substantially as shown and described.
